UNITED STATES PATENT OFFICE

2,326,630

PAINT BURNING AND SCRAPING TOOL

Joseph S. Fagan, Inglewood, Calif.

Application November 6, 1940, Serial No. 364,527

1 Claim. (Cl. 158—18)

My invention relates to a paint burning and scraping tool and has for its principal object to provide a relatively simple, practical, and inexpensive gas fired torch-like tool provided at its forward end with a blade for scraping paint that has been burned and softened by a gas flame that is directed forwardly over the scraping blade and further, to provide a tool having means for effecting a thorough mixture of air with the gas as it passes through the tool and discharges from the forward portion thereof over the scraping blade.

A further object of my invention is, to provide a paint burning and scraping tool of the character referred to wherein the gas flame issuing from the burner that is located rearwardly of the scraping blade is projected forwardly over the blade without directly impinging the same, so as to burn and soften the paint several inches in advance of the sharp edge of the blade, thereby adding materially to the efficiency of the tool in burning and scraping paint.

A further object of my invention is, to provide a paint burning and scraping tool wherein the scraping blade is formed integral with the forward portion of a hollow member that functions as a combined mixing and combustion chamber for the gas and air that pass through the tubular handle of the tool.

With the foregoing and other objects in view, my invention consists in certain novel features of construction and arrangement of parts that will be hereinafter more fully described and claimed and illustrated in the accompanying drawing in which:

Fig. 1 is a plan view of a paint burning and scraping tool constructed in accordance with my invention.

Fig. 2 is a longitudinal section taken on the line 2—2 of Fig. 1.

Fig. 3 is an enlarged cross section taken on the line 3—3 of Fig. 1.

Fig. 4 is an enlarged cross section taken on the line 4—4 of Fig. 1.

Fig. 5 is an enlarged cross section taken on the line 5—5 of Fig. 1.

Referring by numerals to the accompanying drawing which illustrates a preferred embodiment of my invention, 10 designates a metal tube, on the rear portion of which is mounted a handle 11 shaped so as to be conveniently grasped in the hand of the user of the tool and detachably mounted on the rear end of tube 10 is a nipple 12 having a centrally arranged chamber 13 and the wall of the nipple surrounding said

chamber being provided with a plurality of air inlet openings 14.

Screw seated in the rear end of nipple 12 is one end of a valve housing 15 through which is formed a longitudinally disposed duct 16. A rotary valve 17 is arranged for operation in valve housing 15 and said valve being provided with a diametrically arranged port 18 that is adapted to coincide with the duct 16. The outer end of 10 the valve 17 carries a handle 19.

A duct 20, preferably a flexible tube and which leads from a suitable source of gas supply, is connected to the end of valve housing 15 opposite the end that enters the nipple 12.

The forward end of tube 10 is screw seated in a wall 21 that closes the rear end of a short tubular member 22, the chamber within which functions as a combined combustion chamber and a gas and air mixing chamber. Formed through the wall 21 around tube 10 is a series of air inlet openings 23. Formed through the wall of tubular member 22 near its rear end is a series of air inlet apertures 24.

Formed integral with the lower portion of 25 the forward end of member 22 is the rear end of a forwardly and downwardly projecting blade 25 that is substantially triangular when viewed in plan and said blade having a transversely disposed fairly sharp forward edge 26. The forward end of the upper portion of the wall of tubular member is curved downwardly as designated by 27 toward the rear portion of the blade 25 and such construction produces a substantially oval opening 28 directly above the rear portion of blade 25 and the width of which opening is substantially greater than its height.

Thus the jet of flame issuing from the combined combustion and mixing chamber within member 22 is caused to flow forwardly over the inclined blade 25 so as to strike the painted surface on which the tool is being used, several inches in front of the sharp edge of the blade.

Thus the jet of flame issuing from the opening 28 has much greater width than thickness and as a result, an area of considerable width on the painted surface immediately in front of the edge of the blade is impinged by the flame and consequently heated and softened.

While my improved tool is in service, gas passes 50 from duct 20 through the open valve and this gas discharges from the forward end of the valve housing into chamber 13 and from said chamber the gas passes forwardly through tube 10. Inasmuch as the gas is under a certain degree of 55 pressure, its discharge through the chamber 13

into tube 10 will draw air into chamber 13 through the openings 14, which air will mix with the gas passing through tube 10, and this mixture of gas and air will discharge and expand in the chamber within tubular member 22.

Additional air to support combustion of the mixture of gas and air entering and passing through the chamber within member 22 will be drawn through the openings 23 and 24 in the rear portion of member 22 and the resulting mixture when ignited will discharge in the form of a flat flame from the opening 28 at the forward end of member 22 and which flame will impinge and burn the paint on the surface immediately in front of the edge of blade 25.

Immediately after the paint has been softened by the flame, the tool is moved forward so that the sharp edge of the blade will engage and remove the softened paint, thereby accomplishing the desired results.

My improved paint burning and scraping tool is particularly effective in service inasmuch as the shape of the opening 28 at the forward end of the combined mixing and combustion chamber within member 22 flattens the flame as it discharges forwardly over the blade 25 and said flattened flame impinges against and burns a substantial area of the painted surface immediately in front of the blade.

Thus it will be seen that I have provided a paint burning and scraping tool that is relatively simple in construction, inexpensive of

manufacture and very effective in performing the functions for which it is intended.

It will be understood that minor changes in the size, form and construction of the various parts of my improved paint burning and scraping tool, may be made and substituted for those herein shown and described, without departing from the spirit of my invention, the scope of which is set forth in the appended claim.

10 I claim as my invention:

In a paint burning and scraping tool, a hollow cylindrical member provided with a rear wall, a blade formed integral with and projecting forwardly and downwardly from the forward lower portion of said hollow member, there being a single oval shaped jet opening formed in the forward end of said hollow member, the major axis of which oval-shaped opening is horizontally disposed and the bottom of said opening coinciding with the upper surface of the rear portion of the blade so as to direct the single wide jet of burning gaseous fuel that passes through said opening forwardly to strike the surface that is being acted upon, forwardly from the front edge 20 of the blade, a gaseous fuel supply pipe connected to the central portion of the wall closing the rear end of said hollow cylindrical member, and there being a plurality of air inlet apertures 25 formed in said rear wall around the gaseous fuel supply tube connected thereto.

JOSEPH S. FAGAN.
